W. W. HARVEY,
RESILIENT WHEEL,
APPLICATION FILED DEC. 29, 1916.

1,243.735.

Patented Oct. 23, 1917.

UNITED STATES PATENT OFFICE.

WILLIS W. HARVEY, OF MALAD CITY, IDAHO.

RESILIENT WHEEL.

1,243,735.

Specification of Letters Patent. Patented Oct. 23, 1917.

Application filed December 29, 1916. Serial No. 139,587.

To all whom it may concern:

Be it known that I, WILLIS W. HARVEY, a citizen of the United States, residing at Malad City, in the county of Oneida and State of Idaho, have invented certain new and useful Improvements in Resilient Wheels, of which the following is a specification.

This invention relates to certain improvements in resilient wheels and it is an object of the invention to provide a device of this general character having novel and improved means whereby the shocks incident to the travel of the wheel are substantially entirely absorbed.

It is also an object of the invention to provide a novel and improved wheel of this general character wherein the tread portion of the wheel is capable of limited movement relative to the hub when the wheel is under load.

The invention consists in the details of construction and in the combination and arrangement of the several parts of my improved wheel whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be better understood, I will now proceed to describe the same with reference to the accompanying drawings, wherein—

Figure 1 is a view in elevation with portions broken away of a wheel constructed in accordance with an embodiment of my invention;

Fig. 2 is a transverse sectional view taken radially through the device as herein embodied; and

Fig. 3 is a sectional view taken substantially on the line 3—3 of Fig. 1.

As disclosed in the accompanying drawings, 1 denotes a disk of predetermined dimensions and which has its peripheral portion provided with a plurality of substantially equidistantly spaced extensions 2. The extensions 2 are preferably V-shaped in form with their apices disposed outwardly.

The central portion of the disk 1 is provided with a hub structure 3 of any ordinary or preferred arrangement and whereby the device may be readily mounted upon a supporting axle.

Suitably secured to the outer end portion of each of the extensions 2 is a substantially cylindrical block 4 having its opposite side faces concave, as indicated at 5. While the blocks 4 may be secured to the extensions 2 in any desired manner, I find it of advantage to provide each of said blocks 4 with the spaced ears 6 between which is adapted to be received the outer end portion of an extension, and disposed through said ears 6

and the coacting portion of an extension 2 is the securing member 7 which may be a rivet or any other type of holding member which may be employed with convenience and facility.

Overlying the opposite side faces of the blocks 4 are the annular members 8. The face of each of the members 8 adjacent the block 4 is provided with a plurality of concaved pockets or recesses 9 adapted to register with the concave side faces 5 of the blocks 4.

Seated within each pair of registering

all as will be hereinafter more fully set forth,

concavities or recesses 5 and 9 is a spherical

member 10 which has rolling contact with

the walls of said concavities or recesses 5 and 9, whereby it will be perceived that the an-

90 nular members 8 and the blocks 4 are capable of relative independent movement.

Figure 11 denotes an annular rim or felly of a

diameter greater than the maximum diam-

eter of the disk 1 together with its extensions

2 and blocks 4. The disk 1 is arranged

within the rim or felly 11 and is positioned

substantially at the transverse center there-

of. One marginal portion of the rim or

felly 11 is provided with the inwardly dis-

posed integral annular flange 12 which is of

such a radial width as to have its inner mar-

gin terminate inwardly of the extensions 2,

and the inner margin of said flange 12 is dis-

posed inwardly, as at 14, to contact with a

face of the disk 1 so that dirt and other for-

100 eign substances are prevented from passing

outwardly to the peripheral portion of the

disk 1 and more particularly the extensions

2 which would otherwise materially effect

the successful operation of the wheel. I also find it of advantage to provide the contacting portion of the flange 12 with the gasket 15 of suitable material and which directly 5 engages with the adjacent face of the disk 1.

Coacting with the opposite marginal portion of the rim or felly 11 is the removable annular flange 16 which has its inner marginal portion also disposed in a direction toward 10 the disk 1, as indicated at 17, and adapted for contact therewith, the contacting portion of the removable flange 16 also having a gasket 18.

Disposed through the flanges 12 and 16 15 and through the annular members 8 at points intermediate the blocks 4 are the bolts 19 which serve as a means to maintain the removable flange 16 in applied position and also afford a support for the annular members 8. The annular members 8 are capable 20 of movement longitudinally of the bolts 19 but in order to constantly urge the members 8 toward the blocks 4, I employ the springs 20 arranged for contact with the outer faces 25 of the members 8 at points in transverse alignment with the blocks 4.

As is particularly illustrated in Fig. 2, each of the springs 20 has an intermediate bowed portion outwardly directed and which 30 contacts with the inner face of the adjacent flange 12 or 16. The inner end of each of the springs has disposed therethrough a headed member or bolt 21 capable of longitudinal adjustment through either the flange 35 12 or 16, whereby it will at once be self-evident that the pressure exerted by the spring upon an annular member 8 may be readily and conveniently regulated in accordance with the necessities of practice.

40 It is thought to be self-evident that during the travel of the wheel the vibration imposed upon the rim or felly 11 will result in a movement of the annular members 8 independently of the blocks 4 but the shock 45 or jars incident to said vibration will be substantially entirely absorbed by the springs 20 on account of the lateral movement of the members 8 upon the bolts 19.

To prevent any excessive relative movement 50 between the blocks 4 and the annular members 8 which would result in the displacement of the spherical bodies 10, I find it of advantage to interpose between the flanges 12 and 16 at points intermediate the 55 extensions 2, the blocks 22 which blocks are positioned in close proximity to the inner ends of the extensions 2 but spaced sufficiently therefrom as to permit the requisite relative movement between the blocks 4 and 60 the annular members 8.

As herein embodied, the blocks 22 are held in applied position through the medium of the bolts 23 extending axially of the blocks 22 and through the flanges 12 and 16. I

also find in practice that the bolts 23 serve 65 to maintain the inner marginal portions of the flanges 12 and 16 in requisite contact with the opposed faces of the disk 1.

While not essential, I have also found it of manifest advantage to surround the bolts 70 19 intermediate the flanges 12 and 16 with the spacing sleeves 24.

Mounted upon the rim or felly 11 is the tire T of any ordinary or preferred type and, as herein embodied, said tire T is held 75 upon said rim or felly 11 through the medium of the clencher flanges 25 suitably anchored to the outer faces of the flanges 12 and 16. As herein disclosed, the flanges 25 are held to the flanges 12 and 16 through 80 the medium of the bolts 19 hereinbefore referred to.

It is also to be understood that the outer end portions of the springs 20, while contacting with the members 8, are not secured 85 or affixed to said members.

From the foregoing description, it is thought to be obvious that a wheel constructed in accordance with my invention is of an extremely simple and comparatively 90 inexpensive nature and is particularly well adapted for use by reason of the convenience and facility with which it may be assembled, and it will also be obvious that my invention is susceptible of some change and 95 modification without material departure from the principles and spirit thereof and for this reason I do not wish to be understood as limiting myself to the precise arrangement and formation of the several 100 parts herein shown in carrying out my invention in practice, except as hereinafter claimed.

I claim:

1. A resilient wheel comprising a central 105 portion provided in its margin with circumferentially spaced recesses in its opposite faces, annular members arranged at opposite sides of the central portion and provided with recesses adapted to register with the recesses of said central portion, members seated within said registering recesses adapted for rolling contact with the walls thereof, a rim provided with inwardly disposed flanges, members connecting said flanges and loosely disposed through the annular members, flat spring members interposed between the annular members and the flanges for constantly urging the annular members toward the central portion of the 120 wheel, each of said flat spring members having an intermediate bowed portion outwardly directed and in contact with the inner face of the adjacent flange, one end portion of the spring being in contact with 125 the outer face of the annular member, and means engageable with the opposite end of the spring member for securing the same

to the flange, said last named means serving to regulate the tension of the spring member.

2. A resilient wheel comprising a central portion provided in its margin with circumferentially spaced recesses in its opposite faces, annular members arranged at opposite sides of the central portion and provided with recesses adapted to register with the recesses of said central portion, members seated within said registering recesses adapted for rolling contact with the walls thereof, a rim provided with inwardly disposed flanges, members connecting said flanges and loosely disposed through the annular members, co-acting means carried by the flanges and central portion for limiting the circumferential movement of the central portion relative to the annular members, flat spring

members interposed between the annular members and the flanges for constantly urging the annular members toward the central portion of the wheel, each of said flat spring members having an intermediate bowed portion outwardly directed and in contact with the inner face of the adjacent flange, one end portion of the spring being in contact with the outer face of the annular member, and means engageable with the opposite end of the spring member for securing the same to the flange, said last named means serving to regulate the tension of the spring member.

In testimony whereof I affix my signature in the presence of two witnesses.

WILLIS W. HARVEY.
